UNITED STATES PATENT OFFICE.

LEE L. HARTZLER, OF LIMA, OHIO.

CONTINUOUS CROSSING.

1,133,723.

Specification of Letters Patent. Patented Mar. 30, 1915.

Application filed November 12, 1913. Serial No. 800,617.

To all whom it may concern:

Be it known that I, LEE L. HARTZLER, a citizen of the United States, residing at Lima, in the county of Allen, State of Ohio, 5 have invented certain new and useful Improvements in Continuous Crossings; and I do hereby declare the following to be a full, clear, and exact description of the invention, such as will enable others skilled in the 10 art to which it appertains to make and use the same.

This invention relates to railroads, and has special reference to a railroad crossing of an improved type wherein the crossing 15 rails may be made continuous for the passage of a train so that the train may pass over the crossing without jar or shock and thus prevent injury both to the car wheels and to the crossing and road bed.

20 The principal object of the invention is to provide an improved form of railroad crossing wherein the rail, of either of the tracks, may be made continuous for travel over either crossing track.

25 A second object of the invention is to provide an improved mechanism for operating such a crossing.

30 A third object of the invention is to provide a mechanism of improved character having a locking means so that the device may be operative under safety conditions from a signal tower or other operating station.

With the above and other objects in view 35 the invention consists in general of certain novel details of construction and combination of parts hereinafter fully described, illustrated in the accompanying drawings, and specifically claimed.

40 More particularly the invention includes, among other things, a crossing provided with separable rail sections arranged to abut the stationary rails and a filler block for filling the space between the sections 45 when separated, together with suitable mechanisms for operating the same.

In the accompanying drawings, like characters of reference indicate like parts in the several views, and Figure 1 is a plan view 50 of a crossing constructed in accordance with this invention. Fig. 2 is a section on the

line 2—2 of Fig. 1. Fig. 3 is an enlarged detail view on the line 3—3 of Fig. 1. Fig. 4 is an enlarged detail plan view of one of the filler blocks and levers for working the 55 same. Fig. 5 is a section on the line 5—5 of Fig. 3. Fig. 6 is a section on the line 6—6 of Fig. 4. Fig. 7 is an enlarged detail view showing the sliding connection between the stationary and movable rails and also the 60 lever support on the movable rails. Fig. 8 is a detail view of the end of the sliding rail and the guarding rail. Fig. 9 is a side elevation of the end of the sliding rail. Fig. 10 is a section on the line 10—10 of Fig. 1, 65 showing the locking bolt mechanism. Fig. 11 is a section on the line 11—11 of Fig. 10.

It is to be understood that in carrying out the objects of this invention the crossing is provided, as is common in all crossings, 70 with some suitable form of foundation on which the parts hereinafter to be described are firmly fixed. It is not deemed necessary in the present showing to indicate specifically the form of foundation as this may be 75 of any of the usual forms, such as concrete or the like but it is to be understood that certain foundation plates hereinafter referred to as well as the fixed rails and other parts of like character are fixedly supported 80 on such a foundation so that they are immovable relative to each other. Bearing this in mind it is to be noted that at each corner of the crossing there is provided a bed plate 10. The two tracks, which will 85 be indicated respectively as track A and track B, are provided with the approaching rails 11^a and 11^b. These approaching rails are welded or otherwise secured together at each corner of the crossing and their junction point attached to the respective bed plate 10. Outside of the approaching rails at each corner there is provided a guard and base rail 12 of the ordinary type. It will 90 of course be obvious that the rails 11^a on one side of the crossing are alined with the rails 11^a on the other side and in like manner that the rails 11^b on opposite sides of the crossing are also alined. Between the respective pairs of rails 11^a and 11^b are located 95 inside guard rails 13 which have their ends connected by the guard rails 14 which

100

form the outside guard rails or the crossing rails hereinafter to be described. Within the rectangle formed by the four corners or junction points of the rails 11^a and 11^b is an inside guard rail rectangle 15, the rails of which are alined with the respective rails 13. At the sides of this inside guard rail 15 and between said sides and the guard rail 14 are located the sliding crossing rails 16 which are alined with the respective approaching rails 11^a and 11^b and are indicated likewise at 16^a and 16^b for the purpose of distinguishing those rails which pertain to the track A and those rails which pertain to the track B from each other. Each of the rails 16 is provided with a tongue 17 which fits into a suitable slot 18 made in the end of a respective rail 11. This tongue forms a continuation of a portion of the web and the respective rails 16. These rails 16 have their inner ends beveled as indicated at 18 and between the beveled ends 18 is movable a filler rail 19 having correspondingly beveled end and being so arranged that when the rails 16 of each pair are separated so that their end comes in contact with the line rails 11 of the pair the filler rail 19 may be moved into position between said rails 16 so that the inside of the rails 11, 16 and 19 will all be substantially in alinement. For the purpose of preventing a sharp corner from projecting outward and interfering with the movement of the train the filler rails 19 have their heads beveled slightly at the corners as indicated at 20.

The respective rails 14 and 15 are preferably connected together at the bottom by means of a flange 21 forming a continuation of the bases of said rails and this flange is grooved as indicated at 22 to provide a slide for the base of the respective rails 16. In order to hold this rail in position there is also provided a retaining strip 23 which is secured to the flange 21 by suitable bolts 24, the arrangement being readily seen by reference to Fig. 8.

From the foregoing it can be seen that the rails 16^a on each side of the track may be moved apart while the rails 16^b are drawn together and the rails 19 fit in between the respective rails 16^a so the track A is continued or, if the reverse may take place so that the track B is continuous. In order to accomplish this operation simultaneously so that at no time can both tracks be made continuous but each can be made continuous while the other is drawn out of the continuous position so that space is provided between the ends of the respective rails 16 and the line rails of the opposite track for the flanges of passing wheels there is provided certain mechanism which will now be described.

At 25 is a stand whereon is located a

pivot pin 26 on which is pivoted the angle of a bell crank lever 27 one arm of which is connected by a rod 28 which extends to the signal tower or other suitable operating place for the device. To the remaining arm of this lever is connected a rod 29 which is in turn connected to a locking plate 30 having suitable bolt receiving openings 31 formed therein in spaced relation. This plate 30 extends through a slot 31' formed in a locking bolt guide plate 32 and registering with a similar slot formed in one of the rails 14, said plate 32 being normally secured by suitable bolts to said rails 14. On the plate 32 are guide lugs 33 through which passes a pin 34 which is connected, by means of a lever 35 pivoted intermediate its ends to a pin 35' on a stand 37. The remaining arm of this lever 35 is connected to an operating rod 38 which also extends to the tower. Now, it is to be observed that if the pin be in position through one of the bolt or pin receiving openings 30' the lock bar 30 cannot be moved by the connecting rod 28. If however the pin be withdrawn the lock bar 30 can then be moved. By suitably connecting the bars 28 and 30 to the interlocking mechanism arrangement may be made whereby the usual warning signal can be set along either track. This connection, however, has no part of the invention and is accordingly not shown or described.

Connected to the locking bar 30 is a rod 39 which passes through a suitable opening in the guard rail 15, this opening being alined with the opening 31 and this rod is screwed into the sleeve 40 of a bracket 41 which is provided with a forked end 42 wherein is fixed a plate 43 having pivot openings 44 at its end. At 45 are certain lever supports which are located centrally of the rails 14 and securely bolted thereto. Each of these lever supports is provided with a pair of spaced pivot pins 46 and on these pivot pins are pivoted the bell crank levers 47. These bell crank levers 47 each have one arm connected by a pin 48 with a respective opening 44 in the plate 43 so that as this plate is moved the levers 47 will be operated. The remaining arm of each lever 47 is connected by a pin 49 to a bracket 50 securely bolted to one of the sliding rail members 16. Now it will be observed that as the bracket 41 is moved toward the center of the crossing the sliding rail members 16 to which the respective brackets 41 are attached will be moved toward each other while, when the bracket is moved away from the center of the crossing the sliding rail members will be moved away from each other. In order to effect this movement simultaneously in all four sets of the members or rails 16 the bracket 40 which is attached to the rod 39 has connected thereto a rod 51 which carries a bracket 52 similar

in all respects to the bracket 41 and similarly provided with a plate 43. This plate 43 is connected to one arm of each of a pair of bell crank levers 53 which are pivoted on pins 54 supported on suitable fixed stands 55. The remaining arms of these bell crank levers 53 are connected to rods 56 and these rods are in turn connected to brackets 57 similar in all respects to the brackets 41 but connected to the rails at right angles to the rails to which the bracket 41 is connected. The bracket 52 is also connected to an extension 58 of the rod 51 and this extension 58 has its end pivotally connected to one arm 15 of a bell crank lever 59 which is supported on a suitable pivot pin 60 carried on a plate 61. The remaining arm of the bell crank lever 59 is connected to a second bell crank lever 62 also supported on the plate 61 by 20 means of a pivot pin 63. The remaining arm of this bell crank lever 62 is connected to a rod 64 which carries a bracket 65 similar in all respects and similarly connected to its rail 16^a as the bracket 41. Thus all of 25 the rails 16 are connected to and operated by the movement of the rod 28. In order to operate the filler rails 19 these rails are connected respectively to the bar 39 and to bars 66 carried by the respective brackets 30 57 and 55. This arrangement can be best seen by reference to Fig. 3 where it will be noted that these bars 66 are fast through a suitable opening in the web of the respective rail 19 as indicated at 67 and on each side of 35 said web there is provided the nut 68 which serves to hold the rail 19 in position on the respective bar 66. Moreover these bars 66 are provided with flat extensions 69 which pass through suitable slots 70 formed in the 40 respective rails 14 so that the rails 19 are properly guided.

Now, considering the parts in position shown in Fig. 1 if the rod 38 be moved in the direction of arrow the bolt will be withdrawn from the locking bar 30 so that the rod 28 can then be moved in the direction of 45 its arrow. When this takes place the filler block 19 on each side of the crossing will be withdrawn and the rails 16^a on each side of said crossing will be drawn toward each other. At the same time the rails 16^a on each side of the crossing will be forced apart while the 50 filler blocks 19 will be positioned between the ends of the respective pairs of rails 16^a. It is to be noted that when these parts are in 55 position, as can be seen in Fig. 1, there is formed practically a continuous rail including the rails 11^b, 16^b and filler rails 19.

There has thus been provided a simple 60 and efficient device of the kind described, and of the character specified.

It will be obvious that many minor 65 changes may be made in the form and construction of this invention without departing from the material principles thereof. It

is not therefore desired to confine the invention to the exact form herein shown and described, but it is wished to include all such as come properly within the scope claimed.

Having thus described the invention, what 70 is claimed as new, is:—

1. In a railroad crossing, alined stationary rails, separable rails arranged in sets located between pairs of the alined rails and movable longitudinally into and out of butting engagement with the respective stationary rails, beveled members adapted to fill the space between said separable rails when outwardly displaced and a system of bell crank levers to move one set of separable 75 rails into engagement and the other set out of engagement and to push said beveled members into engagement with said outwardly displaced rails simultaneously.

2. In a railroad crossing, alined stationary rails, separable rails arranged in sets in alinement with respective pairs of stationary rails, filler blocks movable into and out of alinement with said separable rails, pairs of bell crank levers, respective pairs being 80 fulcrumed adjacent to respective pairs of separable rails to move one set of separable rails into engagement and the other set out of engagement and means connected with said pairs of bell crank levers to push said 85 filler blocks into and out of alinement with said separable rails.

3. In a railroad crossing, a bed plate, a track including a pair of rails and a second pair of rails alined with but spaced from the first pair, a second track at an angle to the first and including similarly alined and spaced rails, guard and base rails integral with said bed plate attached externally to said respective first pairs of rails at the intersection of said tracks, protractile and retractile filling elements arranged in the spaces of the respective tracks, and arranged to completely fill the respective spaces, and means to move the elements oppositely in 100 105 the respective tracks.

4. In a railroad crossing, a pair of alined and spaced rails, separable rails alined with said rails and having their adjacent ends beveled, a wedge shaped filler rail movable 110 into and out of the space between the beveled ends, and a system of bell crank levers to operate the separable rails and filler rails simultaneously.

5. In a railroad crossing, a pair of alined and spaced rails, a web, separable rails sliding in said web alined with said rails and having their adjacent ends beveled, a second pair of alined and spaced rails arranged at an angle to the first named rails, other separable rails alined with the second pair of rails and having their ends beveled, filler blocks movable into and out of alinement with the separable rails, and means operable 115 120 125 simultaneously to move one pair of separable 130 rails.

rails apart and insert the filler block therebetween, and move the second pair of filler rails together and withdraw the filler block.

6. In a railroad crossing, a pair of alined and spaced rails, separable rails alined with said rails and having their adjacent ends beveled, a second pair of alined and spaced rails arranged at an angle to the first named rails, other separable rails alined with the second pair of rails and having their ends beveled, filler blocks movable into and out of alinement with the separable rails, means operable simultaneously to move one pair of separable rails apart and insert the filler block therebetween, and move the second pair of filler rails together and withdraw the filler block, said means comprising pairs of bell crank levers, each pair being fulcrumed adjacent a respective pair of separable rails, one arm of each being connected to a respective separable rail, brackets each connecting the remaining arms of a respective pair of levers, rods connected to respective brackets and filler blocks, and a linkage connecting said brackets and arranged to move one bracket toward and the other away from the center of the crossing.

7. In a railroad crossing, an inside guard rail rectangle separable rails alined with said rails and having their adjacent ends beveled, said separable rails and first mentioned rails having a tongue and slot connection, a wedge shaped filler rail movable into and out of the space between the beveled ends, and bell crank levers passing through slots in said guard rail rectangle to operate the separable rails and filler rails simultaneously.

8. In a railroad crossing, alined stationary rails, separable rails arranged in sets located between pairs of the alined rails and movable longitudinally into and out of butting engagement with the respective stationary rails, a system of bell crank levers to move certain sets of separable rails into such engagement and other sets out of such engagement simultaneously, and a locking device to hold said means releasably from movement.

9. In a railroad crossing, alined stationary rails, separable rails arranged in sets in alinement with respective pairs of stationary rails, filler blocks movable into and out of alinement with said separable rails, a system of bell crank levers to move said rails apart and together, other means connected to the first means to move said filler blocks into and out of alinement with the separable rails, and a locking device to hold said means releasably from movement.

10. In a railroad crossing, a track including a pair of rails and a second pair of rails alined with but spaced from the first pair, a second track at an angle to the first and in-

cluding similarly alined and spaced rails, 65 protractile and retractile filling elements arranged in the spaces of the respective tracks, and arranged to completely fill the respective spaces, a system of bell crank levers to move the elements oppositely in the respective tracks, and a locking device to hold said means releasably from movement.

11. In a railroad crossing, a pair of alined and spaced rails, separable rails alined with said rails and having their adjacent ends beveled, a wedge shaped filler rail movable into and out of the space between the beveled ends, a system of bell crank levers to operate the separable rails and filler rails simultaneously, and a locking device to hold 80 said means releasably from movement.

12. In a railroad crossing, a pair of alined and spaced rails, separable rails alined with said rails and having their adjacent ends beveled, a second pair of alined and spaced rails arranged at an angle to the first named rails, other separable rails alined with the second pair of rails and having their ends beveled, filler blocks movable into and out of alinement with the separable rails, and bell 90 crank levers operable simultaneously to move one pair of separable rails apart and insert the filler block therebetween, and move the second pair of filler rails together and withdraw the filler block, and a locking 95 device to hold said means releasably from movement.

13. In a railroad crossing, a pair of alined and spaced rails, separable rails alined with said rails and having their adjacent ends 100 beveled, said separable rails and first mentioned rails having a tongue and slot connection, a wedge shaped filler rail movable into and out of the space between the beveled ends, means to operate the separable 105 rails and filler rails simultaneously, and a locking device to hold said means releasably from movement.

14. In a railroad crossing, a pair of alined and spaced rails, separable rails alined with 110 said rails and having their adjacent ends beveled, a second pair of alined and spaced rails arranged at an angle to the first named rails, other separable rails alined with the second pair of rails and having their ends 115 beveled, filler blocks movable into and out of alinement with the separable rails, means operable simultaneously to move one pair of separable rails apart and insert the filler block therebetween, and move the second 120 pair of filler rails together and withdraw the filler block, said means comprising pairs of bell crank levers, each pair being fulcrumed adjacent a respective pair of separable rails, one arm of each lever being connected to a respective separable rail, brackets each connecting the remaining arms of a respective pair of levers, rods connected to

respective brackets and filler blocks, a linkage connecting said brackets and arranged to move one bracket toward and the other away from the center of the crossing, and
5 means to lock said linkage releasably from movement.

In testimony whereof, I affix my signature, in the presence of two witnesses.

LEE L. HARTZLER.
